UNITED STATES PATENT OFFICE

160,818

SHIP HULL

Edward J. Sims, San Francisco, Calif.

Application August 8, 1949, Serial No. 4,358

Term of patent 3½ years

(Cl. D71—1)

To all whom it may concern:

Be it known that I, Edward J. Sims, a citizen of the United States, residing at San Francisco, county of San Francisco, and State of California, have invented a new, original, and ornamental Design for a Ship Hull, of which the following is a specification, reference being had to the accompanying drawing, forming part thereof.

Figure 1 is a top plan view of the ship hull, showing my new design;

Figure 2 is a side elevational view;

Figure 3 is a stern view;

Figure 4 is a front elevational view;

Figure 5 is a bottom plan view; and

Figure 6 is a perspective view of a portion of the stern shown in an inverted position.

I claim:

The ornamental design for a ship hull, substantially as shown.

EDWARD J. SIMS.
